UNITED STATES PATENT OFFICE.

JOHN FLAMMANG, OF ST. LOUIS, MISSOURI, ASSIGNOR TO OTTMAR G. STARK, OF ST. LOUIS, MISSOURI.

PISTON.

1,336,690.

Specification of Letters Patent. Patented Apr. 13, 1920.

Application filed May 23, 1918. Serial No. 236,191.

To all whom it may concern:

Be it known that I, JOHN FLAMMANG, a citizen of the United States, residing at the city of St. Louis and State of Missouri, have 5 invented a new and useful Piston, of which the following is a specification.

This invention relates to pistons.

The object of the invention is to provide a piston including a lower portion and an 10 expansive and compressible upper portion of novel construction arranged to expand by the resiliency of the metal, and provided with a novel form of joint between the sections thereof to prevent the passage of gas, 15 steam or other operating agent.

Other objects will appear from the following description in which reference is made to the accompanying drawings illustrating a preferred form of the invention, 20 in which—

Figure 1 is a view partly in section of the casting from which the piston is constructed.

Figs. 2 and 3 are views illustrating the 25 casting after the upper portion thereof has been divided into segmental sections and the holes for the wrist pin formed in the casting.

Fig. 4 is an elevation of the casting after 30 it has been subjected to an additional treatment to close the openings formed by the cutting of the upper portion of the casting into segmental sections.

Fig. 5 is a view of the casting after the 35 upper portion thereof has been finished as to its circumferential surface.

Fig. 6 is a view partly in section after the wrist pin has been placed in the casting and the casting has been finished.

40 Fig. 7 is a view showing the piston body after the same has been finished.

Fig. 8 is a view of the finished piston having the top or head plate in connection therewith.

45 Fig. 9 is a view of the piston within a cylinder.

The casting from which the piston body is manufactured includes a lower ring 1, an upper ring 2, connections 3 integrally 50 uniting the lower and upper rings, and bosses 4 extending inwardly from the connections 3, said bosses constituting supports for the wrist pin. The casting thus con-

structed is treated to make the upper ring 2 expansive and compressible so that when 55 placed within a cylinder the upper portion of the piston will impart pressure against the wall of the cylinder all around and thus dispense with the necessity of using piston rings or packing in connection with the 60 piston. For this purpose the connections 3 are cut inwardly from their opposite side edges as shown at 5. The cuts 5 extend preferably somewhat less than half the 65 width of the connections 3, and each of the cuts 5 is intersected by a cut 6 extending to the upper edge of the ring 2, thus dividing the upper portion of the casting into segmental sections which are independently supported by the connections 3 respectively. 70 As shown, the cuts 6 are oblique or inclined relative to the axis of the piston body and this is the preferred construction, though it is apparent that the cuts 6 may be otherwise formed if desired. The cuts 6 are also 75 preferably inclined relative to the radii of the casting so that the inner portion of each segmental section engages or extends under the adjacent segmental portion.

Holes 7 are formed through the connections 3 and the bosses 4 for receiving the wrist pin of the piston. As shown the holes 7 are inclined inwardly and downwardly, so that when the wrist pin 8 is placed therein the connections 3 will be forced apart and 85 placed under tension.

After the upper portion of the piston body has been divided into segmental sections, the sections are treated in order to cause the ends of the segmental sections to 90 close the openings or cuts 5. The treatment consists in pressing the ends of the segmental sections into contact with the connections 3 from which the ends are separated by the cuts 5 and subjecting the piston to 95 treatment to cause the segmental sections to retain that position. The treatment may consist in heating the piston to a dull red heat which is sufficient to change the molecular arrangement of the segmental sections 100 and so that they will remain with their ends in contact with the connections 3, thus permanently closing the cuts or openings 5, as shown in Figs. 4 and 5. This treatment may be effected either before or after the 105 wrist pin is mounted on the piston body as

desired. The depression of the ends of the segmental sections of the upper ring of the piston body places them approximately in the position shown in Fig. 4, and thereafter 5 the upper end of the piston body is ground or finished to provide a properly smooth surface upon which the head or top plate of the piston is to be mounted.

The head or top plate of the piston is 10 illustrated in Figs. 8 and 9 and comprises a disk 9 having an annular flange 10 extending into the upper portion of the piston. The flange 10 may also be formed with a circumferential flange 11 which will engage in 15 a groove formed inside the upper ring of the piston body thus forming an interlocking connection between the top or head plate of the piston and the piston body. Also, if desired, keys 12 in the form of thin plates 20 may be seated in the slots in the upper portion of the piston body and engaged within notches or recesses in the flange 10 of the top plate.

The diameter of the head or top plate 9 25 is approximately that of the cylinder for which the piston is intended while the diameter of the upper portion of the piston body comprising the segmental sections of the ring 2 is held under tension to a diameter slightly in excess of that of the cylinder for which the piston is intended. The diameter of the lower portion of the piston body is slightly less than the diameter of the cylinder in which the piston is to be 30 used and, when the piston is placed within the cylinder, the expanded upper portion of the piston is compressed so that a close fit is formed. Thus, the resiliency of the metal is utilized to press the upper portion of the 35 piston against the cylinder wall throughout the circumference of the piston, and since the extremities of the segmental sections of the ring 2 are overlapped at or near the radial lines along which the expansion is 40 effected by the resiliency of the connections 45 3, it is clear that pressure is imparted against the cylinder wall throughout the entire circumference of the piston and that this pressure is approximately uniform at 50 all points.

My improved piston therefore dispenses entirely with the need of piston rings or packing of any character and the resiliency of the material of the piston is utilized to 55 impart pressure uniformly against the cylinder wall at all points throughout the circumference of the piston.

The piston thus constructed is simple and easily applied, and being provided with a 60 removable top or head plate can be readily repaired in case any of the parts become broken or damaged.

What I claim and desire to secure by Letters Patent, is:—

65 1. A piston composed of a hollow body

whose upper portion is divided into segmental sections having overlapping ends, said upper portion being of larger diameter than the diameter of the lower portion of the body.

70

2. A piston composed of a hollow body whose upper portion is of larger diameter than the lower portion, and said upper portion being divided into segmental sections having overlapping ends which are held 75 under tension whereby the resiliency of the metal will press the segmental sections against the wall of the cylinder in which the piston is mounted.

3. A piston comprising a hollow body 80 whose upper portion is divided into segmental sections having overlapping ends, said upper portion being of a diameter in excess of the diameter of the lower portion of the body and of the diameter of the cylinder for which the piston is intended, and being compressible into the cylinder, whereby when the piston is placed in the cylinder the segmental sections of the upper portion of the piston will be pressed against the 85 cylinder wall by the resiliency of the metal.

4. A piston comprising a body composed of a lower ring, an upper ring divided into segmental sections having its ends overlapping and being of a diameter in excess of 95 the diameter of the cylinder for which the piston is intended, and connections integrally uniting the segmental sections of the upper ring with the lower ring.

5. A piston comprising a body composed 100 of a lower ring, an upper ring divided into segmental sections having its ends overlapping and being of a diameter in excess of the diameter of the cylinder for which the piston is intended, connections integrally 105 uniting the segmental sections of the upper ring with the lower ring, and a top plate in connection with the upper ring.

6. A piston comprising a body composed of a lower ring, an upper ring divided into 110 segmental sections having its ends overlapping and being of a diameter in excess of the diameter of the cylinder for which the piston is intended, connections integrally uniting the segmental sections of the upper ring with the lower ring, a top plate mounted on the upper ring, and means removably holding the top plate in connection with the upper ring of the piston.

7. A piston comprising a body composed 120 of a lower ring, a number of segmental sections forming an upper ring, and connections integrally uniting the segmental sections of the upper ring with the lower ring, the free ends of the segmental sections bearing 125 upon adjacent connections.

8. A piston comprising a body composed of a lower ring, a number of segmental sections forming an upper ring, connections integrally uniting the segmental sections of 130

the upper ring with the lower ring, the free ends of the segmental sections bearing upon adjacent connections, and a wrist pin secured to said connections.

6 9. A piston comprising a body composed of a lower ring, a number of segmental sections forming an upper ring, connections integrally uniting the segmental sections of the upper ring with the lower ring, the free 10 ends of the segmental sections bearing upon adjacent connections, a wrist pin secured to

said connections, and a top plate connected to the upper ring.

10. A piston comprising a body composed of a lower ring, a number of segmental sections forming an upper ring, and connections integrally uniting each of said sections with the lower ring and constituting a support for the free end of the adjacent section, and a top plate in connection with the upper ring. 15 20

JOHN FLAMMANG.
